(57) **CLAIM**

The ornamental design for a flower arranging device for a vase, as shown and described.

DESCRIPTION

FIG. 1 is a perspective view of a flower arranging device for a vase showing our design, the flower arranging device shown in a flat condition prior to use.

FIG. 2 is a front view thereof, it being understood that the opposite side to that shown is a mirror image thereof.

FIG. 3 is a top view thereof.

FIG. 4 is a bottom view thereof.

FIG. 5 is a left view thereof.

FIG. 6 is a right side view thereof; and,

FIG. 7 is a perspective view thereof, the flower arranging device shown in a folded condition ready for use.
